UNITED STATES PATENT OFFICE

JOHN S. FRIDOLPH, OF NEW YORK, N. Y., ASSIGNOR, BY MESNE ASSIGNMENTS, TO
SAMUEL J. BENOIT, OF LEOMINSTER, MASSACHUSETTS

DESIGN FOR A TOY AEROPLANE

Application filed May 21, 1929. Serial No. 31,322. Term of patent 3½ years.

To all whom it may concern:

Be it known that I, JOHN S. FRIDOLPH, a citizen of the United States, and a resident of the city, county, and State of New York, have invented a new, original, and ornamental Design for Toy Aeroplanes, of which the following is a specification, reference being had to the accompanying drawings, forming a part hereof.

Figure 1 is a plan view and Figures 2 and 3, side and front elevational views respectively, of a toy aeroplane, showing my new design.

I claim:

The ornamental design for a toy aeroplane, substantially as shown.

JOHN S. FRIDOLPH.
